5 Sheets-Sheet 1

This technical cross-sectional diagram illustrates a complex mechanical assembly, possibly a cylinder or pump, featuring two main vertical sections. The left section includes a base with a valve (92), a piston rod (100), a piston (101), and a cylinder body (102). The right section contains a piston rod (105), a piston (106), and a cylinder body (107). Numerous internal components are labeled with numbers such as 1, 2, 3, 4, 5, 6, 7, 8, 9, 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, and 100. The diagram uses lines and arrows to show the flow of fluid and the movement of various parts within the assembly.

UNITED STATES PATENT OFFICE.

WILLIAM H. WALDRON AND LYNN B. CASE, OF NEW BRUNSWICK, NEW JERSEY, AS
SIGNORS TO JOHN WALDRON CORPORATION, OF NEW BRUNSWICK, NEW JERSEY, A
CORPORATION OF NEW JERSEY.

PRINTING MACHINE.

Application filed October 18, 1926. Serial No. 142,331.

Our invention relates to printing machines of the multi-color type such as those employed in printing a design upon the pre-coated surface of floor coverings, etc., especially those of the larger proportions, for example, a single piece rug nine feet by twelve feet.

A machine constructed in accordance with the principles of our invention comprises a plurality of substantially identical printing units; and each unit comprises a printing roll of such diameter that the color applied by the printing roll thereof will be applied to a full rug by a single revolution 15 of the printing roll, thus the range of design is unlimited, as no repeats are necessary to complete the full rug as in the machines in use at the present time. Each unit also includes the necessary color pan and rolls for 20 applying the color to the print roll.

The details of construction of the print roll employed in our improved printing machine are described and claimed in our co-pending application, Serial No. 140,497 filed 25 October 9, 1926.

The details of our improved printing machine will be fully disclosed hereinafter, reference being had to the accompanying drawings, of which:

30 Fig. 1 is a plan view of our improved printing machine;

Fig. 2 is a side elevation of the machine;

Fig. 3 is an enlarged side elevation of one of the printing units;

35 Fig. 4 is an end elevation of the mechanism shown in Fig. 3;

Fig. 5 is a longitudinal sectional elevation taken on the line 5—5 of Fig. 4; and

40 Fig. 6 is a transverse sectional elevation taken on the line 6—6 of Fig. 3.

Referring to Figs. 1 and 2 of the drawing, our improved printing machine comprises a plurality of printing units 1, 1 coupled in tandem and provided with a feeding unit 45 2 at one end.

Each printing unit 1 comprises a main frame consisting of side members 3 and 4 suitably and rigidly spaced apart by cross ties 5, 5. Secured to each of the side frames 3 and 4 is a bearing standard 6 and 7 respectively. Each bearing bracket is provided with a vertical channel 8 having a flange 9 extending around the two vertical sides and the bottom of the said channel 8.

A printing roll 10 is suitably mounted on 55 a supporting shaft 11 which is journaled in bearing blocks 12, 12 mounted in the channels 8, 8 of the standards 6 and 7 respectively. Filler blocks 13, 13 and 14 are disposed in the channels 8 intermediate the base thereof 60 and the bearing blocks 12, 12. The filler blocks 14 are each provided with a jack screw 15 which bears against the lower side of the respective bearing blocks 12 for adjusting, aligning and levelling the printing 65 roll 10 in a vertical plane. Each bearing standard 6 and 7 is provided with a cap plate 17 which spans the open end of the channel 8. Each bearing block 12 has a lifting eye 18 secured in its upper face and 70 extending through the cap plate 17, by means of which the print rolls may be removed from the machine.

The bearing blocks 12 are permitted a limited amount of horizontal longitudinal 75 movement in the channels 8, and adjusting screws 16, 16 are adapted to threaded apertures in the flanges 9, 9 and bear against the sides of the said bearing block 12 for minutely adjusting the blocks longitudinally 80 of the machine within the channels 8.

The bearing block 12 in the standard 7 is provided with a bridge element 100 which supports an adjusting screw 101 in axial alignment with the shaft 11. The screw 101 85 has a head 102 positioned in a socket 103 formed adjacent the end of the shaft 11 in a manner permitting the said shaft to rotate relative to the said screw 101. Nuts 104 are provided on the screw 101 and engage the inner and outer faces of the bridge element 100 whereby the shaft 11 and the print roll 10 90 may be adjusted transversely of the machine.

Immediately below each print roll 10 is an impression roll 20 which is secured to a 95 shaft 21 rotatably mounted in a lever 22, at each of its ends. The levers 22, 22 are each pivoted at 23 to the side frames 3 and 4 respectively and the projecting end of each lever is engaged by the end of an adjusting screw 24 which is mounted in a block 25 pivoted to one end of an arm 26. The opposite end of each arm 26 surrounds an eccentric 27 secured to a transverse shaft 28 which is rotatably mounted in the side frames 3 and 4, which is provided adjacent the frame 3 with a hand lever 29, by means of which the impression roll may be quickly released from 100 105

its operative position relative to the respective print roll 10. By the above described mechanism, the relative position of the impression roll 20 may be minutely adjusted and aligned with respect to the said print roll.

Coloring matter is applied to each of the print rolls 10 by means of a suitable color roll 30 which engages the printing face of the respective roll 10, and also is engaged by a feed roll 31. The bottom of the feed roll 31 lies within a color pan 32 which, together with the feed roll 31 and the color roll 30, extends transversely of the machine, the full length of the print roll 10.

The color pan 32 forms the intermediate member of a color carriage 33, the end members of which comprise primary slides 34, 34 which are adapted to slide on extension members 3^a and 4^a of the side frames 3 and 4 respectively. Each primary slide 34 is provided with a downwardly extending flange 35 adapted to slidably interlock with a lateral flange 36 of the respective frame extensions and has formed on its lower edge a gear rack 37, the teeth of which mesh with the teeth of a gear 38. The gears 38, 38 are each secured to a transverse shaft 39 which is rotatably mounted in the said frame extensions and is provided, adjacent the frame extension 3^a with a hand wheel 40 by means of which the color carriage 33 may be moved longitudinally of the machine to accommodate print rolls of different diameters.

Each color roll 30 is secured to a shaft 41 rotatably mounted at each of its ends in a secondary slide member 42 which has a dove-tailed sliding connection 43 with the respective primary slide 34 of the color carriage 33.

Each feed roll 31 is provided with trunnions 44 rotatably mounted each in a bearing 45 slidably mounted on the said secondary slide 42, a dove-tailed connection 46 being provided therebetween. An adjusting screw 47 is rotatably mounted in a lug 48 on the said secondary slide 42 and is threaded into the slidable bearing 45, whereby the feed roll 31 may be adjusted relative to the color roll 30.

The secondary slides 42, and consequently the color roll 30 and the feed roll 31, may be moved relative to the primary slides 34, 34 and color pan 32 for effecting a quick release of the color roll 30 from the print roll 10, by means of a hand lever 50. The hand lever 50 is secured to the end of a shaft 51 adjacent the frame extension 3^a. The shaft 51 is rotatably mounted in bearings 52, 52 secured to the respective primary slides 34 and adjacent each bearing 52 an eccentric 53 is secured to the shaft 51. A lever 54 has one of its ends surrounding the respective eccentric 53, and its opposite end pivoted to an adjusting head 56 dove-tailed to and

slidably mounted on each primary slide 34. An adjusting screw 57 is rotatably mounted in each adjusting head 56 and is adapted to a threaded aperture in the secondary slide 42, whereby the color roll 30 may be accurately aligned with the print roll 10.

The material to be printed is conveyed through the machine by means of tapes 60, 60 which pass around tape wheels 61, 61 and 62, 62 at the opposite ends of the machine. The tape wheels 61, 61 are secured to a transverse shaft 63 rotatably mounted in journal blocks 64, 64 which are slidably mounted in side frames 65 and 66 which are connected to the first printing unit side frame extensions 3^a and 4^a respectively. Tightening screws 67, 67 are threaded into the journal blocks 64, 64 at one end, and are rotatably mounted in bearings 68, 68 at their opposite ends and are held therein against axial movement. A bevelled pinion 69 is secured to the end of each tightening screw 67 and meshes with a bevelled pinion 70 secured to a transverse shaft 71 adjacent each of the side frames 65 and 66. A hand wheel 72 is secured to the shaft 71 adjacent the side frame 65.

The feed tapes are provided with pins 73 which are spaced apart throughout the entire run of the tapes and are adapted to pierce the material to be printed adjacent the edges thereof, and at each side of the machine a shoe 74 is provided for riding in top of the material and pressing it onto the said pins 73.

Each tape 60 rides in guides 75, 75 which extend between the impression rolls 20, 20 and the impression roll 20 of the first printing unit and the tape wheels 61, 61. The guides 75 are supported by means of brackets 76, 76 secured thereto and to cross braces 77, 77 which extend between the side frames of the machine. The oppositely disposed brackets 76, 76 are connected by angle bars 78 which support a table 79 intermediate the tapes 60, 60 over which the material to be printed is moved by the tapes.

Secured to each print roll shaft 11 is a gear wheel 80 of equal diameter with the printing face of said roll, which meshes with a gear wheel 81 of equal diameter with the face of the impression roll 20 and secured to the shaft 21 thereof. Thus the print roll 10 and the impression roll 20 rotate at equal surface speeds.

Secured indirectly to each print roll shaft 11 is a second gear 82 which meshes with a gear 83 secured to a short shaft 84 rotatably mounted in the side frame 3^a and an extending bearing bracket 85. A worm wheel 86 is also secured to the shaft 84 and meshes with a worm 87 on a lay shaft 88 extending between and rotatably mounted in the brackets 85, 85 of the printing units.

The color roll shaft 41 has secured thereto

a gear 105 which meshes with the gear 82 and the feed roll 31 is driven by a gear 106 on one of the trunnions thereof which meshes with the gear 105, for driving said roll at a 5 surface speed equal to the surface speed of the print roll 10.

Secured to one end of the lay shaft 88 is a beveled gear 89 which meshes with a beveled gear 90 secured to one end of a transversely 10 extending power shaft 91 rotatably mounted in the side frames 3 and 4 of the last printing unit 1, the opposite end of said shaft being provided with a pulley or other equivalent element 92.

15 The tape wheels 62, 62 are secured to a transverse shaft 93 on which is secured a gear wheel 94 which meshes with an idler gear 95. The idler gear 95 meshes with the gear 83 and thus the tapes are moved.

20 The indirect connection of the gear 82 with the shaft 11 of the print roll 10 comprises a worm wheel 96 which is secured to the said shaft 11, and a worm 97 meshing with said worm wheel 96 and being rotatably 25 mounted on the gear 82 in bearings 98, 98. By turning the worm 97, the print roll 10 may be rotated on the shaft 11 and thus the design on the face of the said print roll may be caused to register with the design previously 30 printed on the face of the material, such registry being assisted as to parallel alignment by the set screws 16, 16 as above noted.

In operation the machine is adapted to 35 draw a continuous web of pre-coated material from any suitable source of supply by means of the tapes 60, 60 which convey the web through the machine over the table 79 and between the print rolls 10 and impression 40 rolls 20 of the successive printing units 1, 1. The impression rolls 20 may be quickly

released from the print rolls 10 by the operation of the levers 29 and the color rolls 30 may be quickly released from the print rolls 10 by the operation of the levers 50. 45

The registry of the designs successively printed on the web of material may be accomplished by operation of the worms 97 and the set screws 16.

Print rolls of various sizes may be placed 50 in the machine to print a design on the web of material over an area thereof of dimensions substantially equal to those of the individual rugs to be cut from the web, and the color carriages may be moved bodily in 55 accordance with the diameters of the print roll, by operation of the hand wheels 41.

Proper operating tension may be maintained on the tapes 60, 60 by operation of the hand wheel 72. 60

We claim:

In a printing machine of the class described, a printing unit comprising side frames; a print roll rotatably mounted in said unit; a color carriage slidably mounted on said side frames and comprising primary slides, adapted to said side frames; a color pan secured to said primary slides; secondary slides slidably mounted on said primary slides; a color roll rotatably mounted 70 in said secondary slides; a feed roll engaging said color roll; bearings slidably mounted on said secondary slides in which said feed roll is rotatably mounted; means for adjusting said sliding bearings on said secondary slides; means for adjusting said secondary slides on said primary slides; and means for moving said secondary slides and the adjusting means therefor, relative to said primary slides. 75
